(57) **CLAIM**

The ornamental design for a spray mop, as shown and described.

DESCRIPTION

FIG. 1 is a perspective view taken from the front and right side of a spray mop showing a first configuration of our new design;

FIG. 2 is a right side elevation view of the spray mop shown in FIG. 1;

FIG. 3 is a left side elevation view of the spray mop shown in FIG. 1;

FIG. 4 is a front elevational view of the spray mop shown in FIG. 1;

FIG. 5 is a rear elevational view of the spray mop shown in FIG. 1;

FIG. 6 is a top plan view of the spray mop shown in FIG. 1;

FIG. 7 is a bottom view of the spray mop shown in FIG. 1;

FIG. 8 is a bottom view of the spray mop in use that includes a mop covering disposed over a mop plate; and,

FIG. 9 is a perspective view taken from the front and right side of the spray mop in a third configuration.

The broken lines in the figures illustrate portions of the spray mop that form no part of the claimed design.

1 Claim, 8 Drawing Sheets
